INVENTOR
AMERICA T. MAGUOLO
BY Em. Harrington.

ATTORNEY

UNITED STATES PATENT OFFICE

160,873

PRIE-DIEU

America T. Maguolo, St. Louis, Mo.

Application March 28, 1949, Serial No. 1,680

Term of patent 14 years

(Cl. D29—23)

To all whom it may concern:

Be it known that I, America T. Maguolo, a citizen of the United States of America, residing in the city of St. Louis, State of Missouri, have invented a new, original, and ornamental Design for a Prie-Dieu, of which the following is a specification, reference being had to the accompanying drawing forming a part hereof.

Fig. 1 is a perspective view of a prie-dieu, showing my new design and illustrating same in a folded and closed position, and

Fig. 2 is a perspective view in an unfolded position; and

Fig. 3 is a perspective view in an unfolded position with the top lid in an open position.

I claim:

The ornamental design for a prie-dieu, as shown and described.

AMERICA T. MAGUOLO.
